(57) **CLAIM**

The ornamental design for optics for a light bar, as shown and described.

DESCRIPTION

FIG. 1 is a perspective view looking downwardly from the right side of the front of optics for a light bar which embodies our invention;

FIG. 2 is a plan view of the front thereof;

FIG. 3 is an elevational view from the front thereof, the back elevation view thereof being identical thereto;

FIG. 4 is a plan view of the back thereof;

FIG. 5 is a right end view thereof, the left end view thereof being identical thereto; and,

FIG. 6 is a perspective view looking downwardly from the left side of the back thereof.
